LAMP

Harden Estell, 827 E. 18th St., Oakland, Calif. 94606

Filed Oct. 10, 1972, Ser. No. 295,886

Term of patent 14 years

Int. Cl. D26—05, 02

U.S. Cl. D48—20 C

FIG. 1.

FIG. 2.

FIG. 3.

FIG. 4.

FIG. 5.

FIG. 6.

FIG. 1 is a top plan view of a lamp showing my new design;

FIG. 2 is a front elevational view of the lamp of FIG. 1;

FIG. 3 is an elevational view taken from the right side of the lamp of FIG. 1;

FIG. 4 is a rear elevational view of the lamp of FIG. 1;

FIG. 5 is an elevational view taken from the left side of the lamp of FIG. 1; and

FIG. 6 is a bottom plan view of the lamp of FIG. 1, that portion of the top structure of the lamp which would normally be visible being omitted for convenience of illustration.

I claim:

The ornamental design for a lamp, as shown and described.
